UNITED STATES PATENT OFFICE.

BIRNEY DYSART, OF ST. LOUIS, MISSOURI, ASSIGNOR, BY MESNE ASSIGNMENTS, TO THE DALTON ADDING MACHINE COMPANY, OF CINCINNATI, OHIO, A CORPORATION OF OHIO.

ADDING AND RECORDING MACHINE.

1,209,821.

Specification of Letters Patent. Patented Dec. 26, 1916.

Application filed July 6, 1909. Serial No. 505,972.

To all whom it may concern:

Be it known that I, BIRNEY DYSART, a citizen of the United States, residing at St. Louis, Missouri, have invented a certain new 5 and useful Adding and Recording Machine, of which the following is a specification.

This invention relates to adding and recording machines and has for its object to provide mechanism whereby one of two 10 numbers successively struck on the keys may be subtracted from the other without the necessity of manually filling the full complement of the subtrahend.

Another object is to provide a machine 15 comprising numeral keys, and mechanism operable to add and record numbers struck on the keys, in combination with mechanism for operating said adding mechanism effectively to produce and represent a number 20 which is the remainder or difference between the number or total represented in said adding mechanism and another number subsequently struck on the keys.

Another object is to provide mechanism 25 in an adding and recording machine whereby, after the minuend has been recorded, the complementary "nines" of the subtrahend may be automatically introduced in to the machine without the necessity of being preliminarily struck on the keyboard.

Another object is to provide means for introducing any number of "nines" necessary 30 to constitute the complement of any number to the full capacity of the machine without setting up said "nines" through the medium of the keys.

With these and other objects in view I have embodied my invention in a machine of known construction and have illustrated the 40 same in the accompanying drawings in which:

Figure 1 is a side elevation of such a machine showing a part of my present invention in combination therewith. Fig. 2 is a 45 chart or plan of the completed key-board of this machine. Fig. 3 is an illustration of an example of subtraction as ordinarily performed. Figs. 4, 5, and 6 are views illustrative of specimens of work performed on this 50 machine through coöperation of my present invention. Fig. 7 is a vertical sectional view of the rear portion of this machine showing the coöoperative relation of the subject-matter of this invention with the

numbers setting and recording devices of 55 the machine. Fig. 8 is a sectional view further illustrating the coöoperative relation of the present invention with the numbers setting the recording mechanisms. Fig. 9 is a detailed perspective view of the devices 60 whereby any number of complementary "nines" may be filled in. Fig. 10 is a perspective view of the lever by whose operation "1" is added to the unit struck on the keys when the adding mechanism is operated 65 after a number complementary to the subtrahend has been set up in the machine. Fig. 11 is a plan of the cross-carriage and the coöperating parts of the present invention. Fig. 12 is a rear elevation illustrating 70 the relative positions of the cross-carriage and the coöperating parts of present invention.

I have illustrated the subject-matter of the present invention as embodied in a ten-key machine of the cross-carriage type, but it will be understood that by adaptation requiring only the skill of the expert it may be adapted to machines of any construction. A specimen of the machine with which I 80 have illustrated the present invention and which machine is now well known commercially constitutes part of the subject-matter of an application filed by Hubert Hopkins, January 24th, 1903, Serial No. 140,390, and 85 is shown in British Patent Number 854, of 1904. The adding mechanism of that machine, as is well known, includes a key-board of ten digit keys 1 representing all of the ten figures. The levers 2 of the keys 1 extend longitudinally and converge at their 90 rear ends where they are provided with vertical extensions or hammers 3. Rails 4 extend transversely above the rear ends of the levers 2 and, by means of suitable anti-friction devices 5, support a transversely movable carriage 6. A series of rows of pins 7 are mounted in the carriage 6, there being nine pins in each row. The rearmost pin of each row represents "0," the next pin in each 100 row represents the digit "1," and so on to the foremost pins which represent the digit "8." For the digit "9" a plate 8 is attached to the front side of the carriage in advance of the pins representing "8." An escapement bar 9 extends transversely across the levers 2 and communicates with a shaft 10 through an escapement device 11. The up-

per end of the shaft 10 is entrained with the carriage 6 by means of a gear segment 12 and rack 13. A spring 14 actuates the carriage 6 from right to left in the machine, the 5 normal or idle position of the carriage being that in which the row of pins at the left is over the extensions 3, and all pins are depressed. Through the medium of the spring 14 and the escapement mechanism, the carriage 10 is moved one space or row leftwardly when each key is operated. The keys also set up the corresponding pins 7 in the carriage thereby representing or registering the numbers struck on the keys, all of which is 15 well understood.

The numbers thus set up or registered in the carriage may be introduced into and added by the adding wheels 15 by reciprocation of racks 16 which swing from a shaft 20 17 and have heels 18 which strike against the pins 7 that have been set up in the carriage and thereby limit forward movement of the racks and cause the correct number to be introduced and added in the adding 25 wheels. Type-carriers 19 swing from said shaft 17 and have pin-and-slot connection 20 with the racks. A bar 21 is supported in front of the vertical portions of the type-carriers and racks by arms 22 suspended 30 from the shaft 17. Springs 23 connect rearward extensions of the type-carriers with a rod 24 held by projections from the arms 22 whereby movement of said arms will actuate the type-carriers. Type 25 are movably supported at the front ends of the type-carriers and a platen 26 is arranged to hold and feed paper to the type-carriers. Springs 27 connect the rearward projections of the type-carriers with the rear sides of the racks 35 thereby actuating the latter rearwardly with respect to the type-carriers. After the number is set up in the carriage the bar 21 is swung forward and the springs 23 move the type-carriers to recording position, and also 40 move the racks because of the pin-and-slot connections 20. The type-carriers and racks are stopped at proper position to record a number set up in the carriage by the heels 18 on the racks engaging with the pins representing the number. After the type-carriers stop the type 25 at the printing line are 45 automatically driven to record by spring propelled hammers 28 which, at the proper time, are automatically released and thrown 50 against the type effectively to drive the latter to make impressions on the paper. A retaining plate 29 is pivotally supported by the carriage 6 leftwardly from the rows of pins in the carriage and in idle position 55 has its rear edge supported immediately in front of the heels 18 of all the racks, by pin-and-slot connection 29^b with a spring-held plate 29^b, thereby preventing movement of the racks except when a number is represented 60 in a carriage. As the carriage travels

leftwardly the plate 29 moves successively from its position in front of the heels 18, thereby releasing one rack for each digit in the number set up in the carriage, and preventing movement of the racks in higher orders from the number registered. The plate 29^b protrudes rearwardly adjacent to a rod 29^c which is carried by two arms 29^d attached to a rock shaft 29^e. One of the arms 29^d extends below the shaft 29^e and is pivoted to 75 the rear end of a link 29^f the front end of which, through a series of levers 29^g, is operatively connected to the totals recording key 29^h. Depression of said totals recording key will swing the rod 29^c forwardly and so 80 push forwardly the plate 29^b. This operation draws downwardly the plate 29 below the heels on the racks, and permits the racks and type-carriers to move to record any number or total represented in the adding 85 wheels. These parts are well known, being found in the machines of the type with which I have illustrated my present invention as at present manufactured and sold in the United States. 90

In performing examples of subtraction by the machines as at present constructed the minuend is first registered in the carriage and then introduced in the adding wheels and, if desired, recorded. Then the complement of the subtrahend up to the full capacity of the machine is struck on the keys and introduced into the adding wheels by reciprocating the racks 16. An example of this class of work is illustrated in Fig. 100 3 in which the number A represents the minuend from which the number "125" is to be subtracted. The machine being provided with nine type-carriers requires that six "9's" be first struck on the keys, 105 and then the complement of the number "125" which is "875" be struck on the keys and set up in the carriage. Operation of the racks and type-carriers will introduce this complementary number into the adding 110 wheels, adding it to the minuend already represented therein, and the result will be the difference between the subtrahend number "125" and the minuend. This operation is tedious and requires care on the part of the operator in striking the correct number of "9's" for, should he err in this regard, the result will be incorrect. 115

My present invention overcomes this objection and provides mechanism for automatically taking care of the complementary "9's" without preliminarily introducing them into the machine through the key-board. It also includes a novel arrangement in the key-board whereby the operator may 120 quickly select the complementary keys and thereby more quickly and readily perform the example. 125

In carrying out this invention I provide a key 30 operating through a slot in the case 130

of the machine adjacent to the hammer section and convenient to the operator. The stem of the key 30 is provided with a slot 31 receiving studs 32 and permitting depression of the key. The lower end of the key stem rests upon the projection 33 on the forwardly projecting arm of a bell-crank lever 34 which is pivoted to some stationary part of the machine. A link 35 connects the opposite arm of the bell-crank lever 34 with a lever 36 which is attached to a shaft 37 at the rear of the machine, and is actuated rearwardly by a spring 35a. The lever 38, pivoted to a shaft 39 leftwardly from the 10 group of racks, has one arm extending over the rear edge of the plate 29 and carrying a roller 40. Said lever 38 has another arm extending vertically in front of a pin 41 on the link 35 whereby depression of the key 15 30 will cause the horizontal arm of the lever 38 to press downwardly the spring-held plate 29 from its position in front of the heels 18 which will release all of the racks from detention by said plate. A spring 42 20 is arranged in connection with the lever 38 to support the horizontal arm thereof and to restore the parts actuated thereby to idle position when they are released. The shaft 39 extends transversely behind the racks 18 25 and carries pivoted on its end opposite from the lever 38 a plate 43 having a pin 44 projecting behind the rack in units order and acting normally as a stop or abutment for said rack. When the pin 44 is carried below the end of the rack into the line of movement of the heel 18 the spring 27 thereupon actuates the units rack rearwardly until stopped by the heel 18 striking the pin 44. This movement is arranged to be sufficient for units rack to carry or introduce "1" 30 into the units adding wheel in addition to any units that may be represented therein. A detent or latch spring 45 is arranged to engage in notches 46 in the rear part of the 35 plate 43 thereby to hold said plate and connected parts in either adjustment, but will permit forcible movement of said parts. The rock shaft 37 has attached thereon an eccentric collar 47 which is encircled by the 40 hub of a bell-crank lever 48 having a forwardly extending arm and another arm extending downwardly in front of projections 49 on the plate 43 and one of which is above and the other below the shaft 39. The forwardly extending arm of the lever 48 has a roller 50. When the racks and type-carriers are swung forwardly a link 51 in the machine as now used, (marked 50 in the Hopkins British patent) moves obliquely downwardly and forwardly. The lower edge of this link is provided with a cam surface 52 arranged to operate against the roller 50 without moving the lever 48 and a cam portion 53 at the rear part of the link which 45 operates against the roller 50 and thereby swings the lower arm of the lever 48 rearwardly. A spring 54 sustains the lever 48 in its normal position. When the shaft 37 is rocked by operation of the link 35 the eccentric 47 on said shaft raises the pivotal 70 point of the lever 48 and brings the lower end of said lever immediately in front of the lower pin 49. Upon forward movement of the link 51 the cam 53 thereon causes the lower arm of the lever 48 to engage the pin 75 49 below the shaft 39 and thereby swings the plate 43 to the position shown by dotted lines in Fig. 8. Rearward movement of the racks 16 carries the units rack backwardly until it is stopped by engagement of the 80 heel 18 with the pin 44, which movement is sufficient to cause said rack to introduce into the units total wheel "1" in addition to the digit in units order which had been struck on the key. Release of the key 30 will enable the parts operated thereby, including the eccentric 47, to return to their idle positions. The next movement of the racks and type-carriers and the link 51 will cause operation of the lever 48, bringing a shoulder 90 55 thereon into contact with the upper pin 49 and thereby raising the plate 43 to its normal or idle position in which the pin 44 is in position to engage the rear end of the rack 16. 95

In Fig. 2 I have illustrated a preferred arrangement of the keys 1 in which the large digits represent the digits which said keys will set up in the carriage and the small digits represent the complementary values. 100 Referring to Fig. 4 for further illustration, the minuend A is introduced into the carriage by striking the proper keys with respect to the large characters thereon. It is desired to subtract from the minuend the 105 number "125" which, as previously stated, is accomplished by introducing the full complement of that number into the adding mechanism where it is added to the minuend and the result is the difference between the 110 two numbers. The provision of the small characters on the keys enables the operator readily to select the complementary digits without previous mental calculation. In doing so the operator will simply strike the 115 keys representing the subtrahend by small characters, the complement of "125", as thus determined, being "874" on which keys the digits "1", "2", and "5" are represented by small characters. Having thus introduced 120 the number "874" (or "1" less than the actual complement) as the complement of the number "125" into the carriage the operator then will depress the key 30 thereby depressing the spring-held latch plate 29 by 125 operation of the lever 38. The eccentric 47 being rocked raises the lever 48. Then the type-carriers and racks are swung forwardly in the usual way. The three racks required to introduce into the adding wheels the 130

number represented in the carriage engage against the pins which had been set up to represent the number. The remaining racks swing forwardly over the depressed plate 29 until the heel 18 thereon engage against the "9's" stop plate 8 at the front of the carriage. The rearward movement of the racks introduces the full complement of the subtrahend into the adding wheels. The link 51 at the end of its forward stroke as above described, swings the lower end of the lever 48 against the lower pin 49 and thereby lowers the pin 44 to position that will permit the rack 16 in units order to travel rearwardly one tooth or space. This is necessary for the reason that "874" was set up in the carriage 6 as the complement of "125", whereas the actual complement of the number "125" is "875". The advantage of this construction resides in the fact that it enables the operator at all times to follow the key-board, and the small figures "1", "2" and "5" are found on the "8", "7" and "4" keys, respectively. This additional movement of the units rack 16 actually causes "5" to be added to the unit already represented in units adding wheel instead of "4", and a like operation occurs at each operation of the racks when the subtracting key 30 is depressed. As soon as the racks and type-carriers return to their rearward positions the key 30 is released and the carriage 6 having returned to its idle position at the right of the machine, the plate 29 rises in front of all of the rack heels 18. The eccentric 47 also lowers the lever 48. Then the bar 21 and arms 22, as well as the link 51, are swung forwardly to permit the type-carriers and racks all to return to their idle positions. This movement of the link 51 again operates the lever 48 causing the shoulder 55 thereon to engage the upper pin 49, which raises the front end of the plate 43 to position the pin 44 against the rear end of units rack 16, which completes the operation of subtraction and causes the remainder number to be retained in the adding wheel, such number being shown at B in Fig. 4.

It is also well known that the machines 50 of the type illustrated are operable to add, subtract, or multiply numbers without recording them. The means for accomplishing this result includes what is called "non-print" lever or key 56 arranged adjacent to the printing hammers 28. By holding the lever 56 in its depressed position while the type-carriers and racks are operating, the number in the carriage will be introduced into the adding-wheels, and the paper will be fed one line space around the platen without making any record of the number added. The lever 56 is connected to a plate or bar which is movable by said lever into the path of the printing hammers so as to prevent 65 their striking against the type. This pre-

vents record being made of any number added and which would have been recorded had the hammers been allowed to strike the type. This may also be done in performing examples of subtraction by my improved mechanism, in which instance it is desirable that the subtrahend complement be not recorded. A specimen of this work is shown in Fig. 5 in which the minuend and remainder are recorded, but the subtrahend complement is 75 not recorded. For convenience of operation I have positioned the subtraction key 30 in proximity to the "no-print" key or lever 56 so that both may be operated at the same time without the slightest inconvenience. 80

It is also well known that these machines include means for preventing addition of numbers which are recorded. This result is effected by depression of a key 57 prior to operation of the racks and type-carriers, 85 said key being held in its depressed position while the racks and type-carriers operate. In Fig. 6 is illustrated a complete example of work by a machine provided with a non-adding key. In this example the minuend 90 A is printed, and the subtrahend C may also be recorded and not added, thereby indicating both the subtrahend and minuend. After the subtrahend and minuend have been recorded in this way the subtrahend 95 complement is added, and, if desired, is recorded, and produces the proper remainder number B. Fig. 6 therefore illustrates every step actually performed in operating the machine for these purposes. 100

I am aware that there may be variations in the arrangement and construction of the parts comprising the present invention without the least departure from the spirit and scope of the invention. I am also 105 aware that with slight modification and adaptations the invention may be applied to various species of adding machines and I do not restrict myself to its combination in machines of any particular class. 110

What I claim and desire to secure by Letters Patent is:

1. In an adding machine, adding wheels arranged in numerical orders, racks for operating said adding wheels, mechanism for reciprocating said racks to operate said adding wheels in adding operations, a pivoted member limiting movement of the rack in units order in one direction, means for positioning said pivoted element in different positions to enable said units rack to move varying distances while actuating the corresponding adding wheel in adding operations, and a device for holding said pivoted element in its different positions. 115 120 125
2. In a machine of the character described, devices adjustable to represent numbers, adding mechanism operable to add said numbers, recording mechanism operable to record said numbers, and mecha- 130

nism for causing said recording mechanism to record a number of greater numerical value than the number represented by said devices or said adding mechanism in certain 5 operations of the machine.

3. In a machine of the character described, a carriage, devices in said carriage adjustable to represent numbers, and recording mechanism operable to record numbers represented in said carriage, in combination with means for causing said recording mechanism to record a number of greater numerical value than the number represented in said carriage.

10 4. In an adding machine, the combination of a series of racks, an element for holding said racks in their idle positions, a device for moving said element in one direction to release predetermined numbers 20 of said racks for adding operations, adding mechanism operated by said racks in adding and clearing operations and means for moving said element in another direction to release said racks for adding operations in 25 any position of said device.

5. In an adding machine, the combination of a series of adding wheels, a series of racks for operating said adding wheels in adding operations, an element holding said 30 racks in idle position, a device for moving said element in one direction to release predetermined numbers of said racks in adding operations and an independently operable device for moving said element in another 35 direction to release said racks for adding operations in any position of said first-named device.

6. In an adding machine, adding wheels, racks for operating said adding wheels in 40 adding and subtracting operations, an element for holding said racks, a device for moving said element in one direction to release varying numbers of said racks, a series of keys each of which controls the release 45 of said element from any desired number of said racks, means for moving said element in another direction to release said element from said racks, and an independent device for releasing said element 50 from said racks in clearing operations.

7. In an adding machine, the combination with a series of reciprocating racks operable in adding and clearing operations and a device for holding said racks in their 55 idle positions, of means for moving said device in one direction to release varying numbers of said racks, means for moving said device in another direction to release an additional number of said racks for 60 clearing operations, and means for moving said device to release all of said racks for clearing operations.

8. In an adding machine, a series of racks, differential mechanism for limiting 65 movement of said racks in adding opera-

tions, an element for holding said racks in their idle positions, mechanism for setting said differential mechanism and moving said element in one direction to release varying numbers of said racks, and means for 70 moving said element in another direction to release an additional number of said racks prior to the operation of said racks, after said differential mechanism has been set.

9. In an adding machine, the combination with a series of reciprocating racks operable in adding operations, an element for holding said racks in their idle positions, differential mechanism for limiting movement of said racks in adding operations and 75 mechanism for setting said differential mechanism and moving said element in one direction to release a predetermined number of said racks, of means under control of the operator for moving said element in the 80 opposite direction to release an additional number of said racks while said differential mechanism remains set as aforesaid, and prior to operation of said racks.

10. In an adding machine, the combination with a series of reciprocating racks operable in adding operations, differential mechanism for limiting movement of said racks in adding operations and an element for holding said racks in their idle positions, 90 of means for moving said element in one direction to release a number of racks equal to the number of digits set in said differential mechanism incidentally to the setting of said number, and optionally operable 95 means for moving said element in another direction to release an additional number of said racks after said element has been moved, as aforesaid.

11. In an adding machine, the combination with a series of racks operable in adding operations and a plate for holding said racks in their idle positions, of means for moving said plate in one direction to release varying numbers of said racks for adding 100 operations, a lever movable into engagement with said plate, and means for operating said lever effectively to move said plate in another direction to release an additional number of said racks after said plate has been 110 moved, as aforesaid.

12. In an adding machine, the combination with a series of reciprocating racks operable in adding operations, a carriage, differential devices mounted in said carriage 120 for limiting movement of said racks, an element in said carriage holding said racks in their idle positions, mechanism for setting said differential devices to limit movement of said racks and moving said element in one 125 direction to release a number of racks equal to the number of digits represented by said differential devices, of a lever for moving said element in another direction to release an additional number of said racks while 130

- 6 said differential mechanism remains set, as aforesaid, and means for operating said lever.
- 5 13. In an adding machine, an adding wheel for each of several numerical orders including units order, a rack for operating each of said adding wheels, transfer devices operating automatically to cause said racks and adding wheels to transfer successively 10 from units order to higher orders, a movable abutment for the rack in units order and a transfer device controlling said abutment whereby the rack and wheel in units order may be caused to perform a transferring 15 operation.
14. In an adding and recording machine, a carriage, means for setting up numbers in said carriage preliminary to adding and recording operations, adding and recording 20 mechanisms, means for operating said adding and recording mechanisms to add and record the numbers set up in said carriage, means for preventing said adding mechanism from adding a number of greater 25 numerical value than the number set up in said carriage, and means under control of the operator whereby said adding mechanism may be operated at selected times to add a number in excess of the number set up 30 in said carriage.
15. In a machine of the character described, a movable carriage, a series of racks, a detaining device supported by said carriage for said racks, adding wheels controlled by said racks, means for operating 35 said racks and wheels in adding operations, and means for releasing said detaining device while said carriage is stationary away from its idle position.
- 40 16. In a machine of the character described, a carriage, a series of ten numeral keys operable to set up in said carriage any desired number within the adding capacity of the machine, adding mechanism, actuating devices controlled by said carriage whereby any number which has been set up in said carriage, and the full complement of "nines" of said numbers may be introduced into said adding mechanism at one 45 operation, and means for operating said actuating devices, substantially as specified.
- 55 17. Subtracting mechanism comprising a number of wheels arranged in numerical orders, a number of racks also arranged in numerical orders for actuating said wheels, a carriage controlling said racks, keys, elements in said carriage settable by said keys to represent the subtrahend, means for operating said racks and said wheels in subtracting operations, and means under control of the operator for causing said racks to introduce into said wheels the full complement of "nines" of any number set up 60 in said carriage irrespective of the position of said carriage.
18. In an adding machine, the combination with adding wheels, reciprocating racks for operating said adding wheels in adding and clearing operations and an element holding said racks in their idle positions, of means 70 for moving said element in one direction to release selected numbers of said racks for adding operations, means for moving said element in an opposite direction, after movement thereof as aforesaid, to release an additional number of said racks for adding operations, and independent means for moving said element in said last-named direction to release all of said racks for clearing operations, substantially as described. 75
19. In an adding machine, type-carriers, racks in connection with said type-carriers, differential mechanism whose operation is necessary before said type-carriers and racks may be operated in certain operations, a total 80 recording key operable to permit operation of said type-carriers and racks independently of an operation of said differential mechanism, and manually operable means independent of said key operable to permit 85 certain of said type-carriers and racks to be operated independently of any previous operation of corresponding parts of said differential mechanism.
20. In an adding machine, adding wheels 90 arranged in numerical orders, racks arranged in numerical orders for actuating said adding wheels, a device holding said racks, differential mechanism for controlling said racks in adding operations, means for 95 setting said differential mechanism to control said racks and also to release said racks and also to release said holding device, and means for releasing said holding device from the remaining racks after said differential mechanism has been adjusted to control certain of said racks, and means for operating all of said racks in adding operations after said holding device has been released as aforesaid. 100
- 110 21. In an adding machine, adding wheels arranged in numerical orders, racks also arranged in numerical orders for actuating said adding wheels, means for operating said racks and wheels in adding operations, a pivoted plate for preventing operation of said racks, a lever engaging said plate, a key, connections from said key for operating said lever to release said plate, and means for operating said actuators and adding mechanism in adding operations while said plate is retained in released adjustment by operation of said key, substantially as specified.
- 115 22. In an adding machine, adding wheels, racks for actuating said adding wheels, means for operating said racks, and a detaining device holding said racks, in combination with a lever for moving said detaining device, a spring holding said lever 120
- 125
- 130

disengaged from said detaining device, a link for operating said lever and thereby said detaining device to permit operation of said racks in adding operations, and a key
5 for operating said link, substantially as specified.

In testimony whereof I have affixed my

signature and seal to this specification this 25th day of June 1909, in the presence of two subscribing witnesses.

BIRNEY DYSART. [L.S.]
